UNITED STATES PATENT OFFICE.

CHARLES E. McGONIGLE, OF WEST SUPERIOR, WISCONSIN.

DESIGN FOR A BROILER AND TOASTER.

SPECIFICATION forming part of Design No. 24,343, dated May 28, 1895.

Application filed September 22, 1894. Serial No. 523,842. Term of patent 7 years.

To all whom it may concern:

Be it known that I, CHARLES E. McGONIGLE, a citizen of the United States, residing at West Superior, in the county of Douglas and State of Wisconsin, have invented a new and original Design for Broilers and Toasters, of which the following is a specification.

This invention relates to a new and original design for broilers and toasters; and it has for its object to provide a design of this character that shall be both useful and ornamental.

The leading feature of the design resides in a rectangularly shaped body provided on its upper face with closely arranged parallel rows of truly pyramidal figures covering the entire area of the body up to a point directly adjacent to its edge, a plain narrow marginal space bounded by the outermost rows of pyramidal figures and the peripheral edge of the body, and outwardly extending curved U-shaped figures arranged at diametrically opposite edges of the body.

In the drawings, Figure 1 is a plan view of a broiler and toaster embodying the herein-described design. Fig. 2 is an elevation of the same.

Referring to the drawings, the numeral 1

designates a rectangularly shaped body provided on its upper face with closely arranged parallel rows of truly pyramidal figures 2, 3° forming intervening spaces arranged parallel and extending across the body at right angles, said pyramidal figures covering the entire area of the body up to a point directly adjacent to its edge. The body 1, is further 35 provided with a narrow plain marginal space 3, bounded by the outermost rows of pyramidal figures and the peripheral edge of the body, and the design is completed by the U-shaped figures designated by the numeral 4. 4° The said U-shaped figures are located at diametrically opposite sides of the body and are extended upwardly and outwardly on a slight curve.

What I claim is—

The design, for broilers and toasters, herein shown and described.

In testimony that I claim the foregoing as my own I have hereto affixed my signature in the presence of two witnesses.

CHARLES E. McGONIGLE.

Witnesses:

W. D. DWYER,

LOUIS HANITCH.
